UNITED STATES PATENT OFFICE

146,523

DESIGN FOR A STOVE

Lauren R. Reynolds, Joplin, Mo.

Application December 5, 1945, Serial No. 124,368

Term of patent 14 years

(Cl. D81—19)

To all whom it may concern:

Be it known that I, Lauren R. Reynolds, a citizen of the United States, residing at Joplin, county of Jasper, State of Missouri, have invented a new, original, and ornamental Design for Stoves, of which the following is a specification, reference being had to the accompanying drawing, forming a part thereof.

Fig. 1 is a view partly in top perspective showing the front and one side of a stove embodying my new design;

Fig. 2 is a side perspective view thereof; and

Fig. 3 is a perspective view showing the top, front and other side of the stove shown in Figures 1 and 2.

I claim:

The ornamental design for a stove, as shown.
LAUREN R. REYNOLDS.
